UNITED STATES PATENT OFFICE

HARRY RANNEY HALE, OF MONTREAL, QUEBEC, CANADA, ASSIGNOR TO HALE BROTHERS LIMITED, OF MONTREAL, CANADA

ELECTRICAL SOCKET

Application filed September 9, 1929. Serial No. 391,431.

The invention relates to an electrical socket, as described in the present specification and illustrated in the accompanying drawings that form part of the same.

5 The invention consists essentially of the novel features of construction pointed out broadly and specifically in the claim for novelty following a description containing an explanation in detail of an acceptable form 10 of the invention.

The objects of the invention are to eliminate the use of metal in so far as it is possible to do so in the manufacture of electrical sockets, keyless and otherwise as the case may be, and thereby produce an article that will 15 in itself form the frame of the casing for the electrical contacts, and at the same time be extremely efficient in operation and less liable in conventional sockets to get out of 20 order; to reduce the cost of production and modernize electrical socket equipments of this particular class so that the newer methods may be used to carry out the complete construction of frame and casing at the least 25 possible expense; and generally to provide in electrical fixtures and parts a durable and reliable socket.

In the drawings, Figure 1 is an elevational view of the socket.

30 Figure 2 is a longitudinal sectional view of the socket.

Figure 3 is an end view of the socket.

Figure 4 is a plan end view of the socket having the cover removed.

35 Figure 5 is a detail of the terminal showing an additional insulation plate disc.

Figure 6 is a longitudinal sectional view of a slight modification of the invention.

40 Figure 7 is a longitudinal sectional view of the socket showing the terminals in an insulating separating plate.

Like numerals of reference indicate corresponding parts in the various figures.

45 Referring to the drawings, the numeral 15 indicates the casing complete including the cap 16, and the partition 17.

The cover or cap 16 is screwed to the body 18, which is externally threaded at 19, the wall of said body tapering slightly at 20 to the shoulder 21 from which the partition 22

extends inwardly to divide the cap body into the socket compartment 26 and the connection compartment 25, all of these parts being made of an insulating composition by means of a molding and pressing operation. 65

The cap 16 is formed with the threaded nipple 24 and is screwed on to the thread 19 and closes one end of the casing and therefore the nipple forms the means for attaching the socket to the electrical connections. 60 Naturally this cap may be altered to suit the type of socket that is made, and the description herein is merely for the better understanding of the invention which is particularly concerned in the partitioned casing 65 forming the connection and socket chambers 25 and 26.

The parallel ribs 27 and 28 extend partially across the bottom surface of the partition 17 and are integral therewith, and between these 70 ribs 27 and 28 the spring electrical contact 29 is rigidly secured to the surface of the said partition, between the ribs 27 and 28, while the threaded barrel contact 30 is secured through the flanges 31 to the partition beyond 75 the ribs 27 and 28, this contact encircling the inner wall surface of the chamber 26 and forming the means of attaching a lamp or other translating device to the socket member, though it must be understood always that 80 other means of attachment may be secured in this connection or terminal chamber.

The electrical terminals 32 and 33 are secured in the connection chamber 25 between the parallel ribs 34 and 35 extending from the partition 22 and crossing said partition 85 and forming part therewith.

These terminals extend upwardly and are flanged at their outer ends 36 and 37 respectively and extend into the slots 38 and 39 in the inner wall surfaces at the upper end, the screws 40 and 41 forming the terminal means of attachment for the wires.

In Figure 6 a slight modification is shown and in this modification the partition 42 is of non-conducting material but is rigidly secured in the casing and supported on the shoulder 43 corresponding to the shoulder 21, in other respects it is exactly the same as the partition 22 forming part with the casing, 100

which is of course the preferable construction.

In Figure 5 the terminals 32 and 33 are shown as slotted at 44 and 45 and the insulating disc 46 is shown as slotted at 47 and 48 and mounted on the terminals for the security in regard to interference, but this in most cases will be found quite unnecessary, yet it is an addition that may be of service.

In the operation of this socket, the wiring 10 is connected to the terminals 32 and 33 and the lamp or other translating device is secured in the inner chamber of the socket, otherwise the socket proper and this translating device forms an electrical connection with the spring 15 contact 29, this spring contact being connected to the terminal 33 by the screw 49 which completes that side of the electrical connection. This screw 49 extends through the partition 22 and is part of the assembly of the 20 socket pieces.

The barrel contact 30 through one of the flanges 31 is secured through a screw 50 to the terminal 32, thus the screw 50 not only serves to secure the barrel contact in place, but also 25 holds the terminal 22 and forms the electrical connection on either side.

The other flange of the barrel contact is secured by the screw 51 which is advantageous in so far as the electrical connection is concerned.

It will thus be seen that a complete socket is made in so far as its casing is concerned, of the latest and most approved material, that is to say, it is complete, ready for the terminals and contacts, whereas in present practice the filling of the casing constitutes the electrical equipment which is both cumbersome and expensive as well as lacking the security of the one piece frame and casing 40 forming the insulation of the socket.

What I claim is:—

An electrical socket comprising a casing of insulating pressed material constituting the screw cap and connection chamber and 45 the reduced socket proper divided from the connection chamber by a ribbed partition of the same material as the casing and pressed and moulded therewith and having threaded holes therethrough, metal connecting members in said socket chamber connected by screws in said threaded holes to terminals in 50 said connection chamber, and a spaced insulating disk slotted and secured to said terminals.

Signed at Montreal, Canada, this 6th day of August, 1929.

HARRY RANNEY HALE.
